ORNAMENTAL PANEL TO SURMOUNT A FENCE

Deane L. Ackerman, 1505 Westridge Place, Casper, Wyo.

Filed Sept. 30, 1964, Ser. No. 81,940

Term of patent 14 years

(Cl. D28—1)

Fig. 1

Fig. 3

FIG. 1 is a front elevational view of an ornamental panel to surmount a fence, showing my new design;

FIG. 2 is a top or bottom view of the panel, and

FIG. 3 is a view taken on line 3—3 of FIG. 1.

I claim:

The ornamental design for an ornamental panel to surmount a fence, as shown.
